United States Patent

Des. 237,947

Patented Dec. 9, 1975

237,947

CONTAINER FOR MATCHES OR THE LIKE

Nobuyoshi Ochiai, 4-18 Kisshiki-cho, Omiya-shi,
Saitama-ken, Japan

Filed Dec. 17, 1973, Ser. No. 424,931

Claims priority, application Japan Oct. 15, 1973

Term of patent 14 years

Int. Cl. D9—03

U.S. Cl. D9—173

FIG. 1

FIG. 2

FIG. 3

FIG. 4

FIG. 5

FIG. 6

FIG. 7

FIG. 1 is a front elevational view of a container for matches or the like showing my new design;

FIG. 2 is a rear elevational view thereof;

FIG. 3 is a right side elevational view thereof, the side opposite being substantially a mirror image;

FIG. 4 is a top plan view thereof;

FIG. 5 is a bottom plan view thereof;

FIG. 6 is a perspective view thereof in a folded condition; and

FIG. 7 is a perspective view thereof in a half-unfolded condition.

I claim:

The ornamental design for a container for matches or the like, as shown.
